UNITED STATES PATENT OFFICE.

NICHOLAS C. STARK, OF ST. LOUIS, MISSOURI.

PENHOLDER.

Application filed August 15, 1924. Serial No. 732,313.

My invention relates to improvements in penholders and has for its primary object an all metal penholder in which the pen point can be reversed so that the same can be 5 readily carried in the pocket.

A further object is to construct an all metal penholder of non-corrosive material so that the same can be readily cleaned of coagulated ink and which when handled 10 by persons having a contagious disease can be readily sterilized.

In the drawings:—

Fig. 1 is a top plan view of my device with the pen point in writing position;

15 Fig. 2 is a side elevation of the same;

Fig. 3 is a top plan view showing the pen point reversed; and

20 Fig. 4 is a side elevation of the holder with a portion thereof broken away and in section showing the slide stops.

In the construction of my device I employ a tapered member 5 which is preferably circular in cross section, and which is provided with rounded ends 6 and 7, the 25 end 7 being the larger. Formed adjacent the end 7 is a recess 8 in which a pin or screw 9 is located. Spaced along the member 5 and at some distance to the rear of the pin 9 is a similar pin or screw 10. These pins 30 are for the purpose of limiting the movement of the sleeve 11. The sleeve 11 is formed of closely coiled spring wire. My purpose of forming this sleeve of spring 35 wire and coiling it is to permit a certain amount of resiliency, but still at the same time enable it to firmly hold the pen point 12 on the member 5 in the position indicated in Figs. 1 and 2 or in Fig. 3.

It is to be understood that the member 5, 40 the pins or screws 9 and 10, and the resili- 45 ent coiled sleeve 11 are made of non-cor- 50 rossive material.

My method of inserting the pen in the 55 holder is as follows: The sleeve 11 is first 60 moved backward on the tapered member 5 until it contacts with the pin 10, the pen 12 is then placed on the member 5 and the 65 sleeve 11 moved forward until the pen is 70 finally bound to the member 5, this binding 75 is accomplished by reason of the fact that 80 in moving the sleeve 11 forward it moves 85 toward the larger end of the member 5 and 90 in this way tightly grips and holds the pen 95 in position. This gripping is further made 100 possible by the fact that the sleeve 11 is 105 formed of coil spring material with the bot-

tom of the coil being free so that a certain amount of expansion is permitted.

When it is desired to place the pen in the position shown in Fig. 3 the sleeve 11 is 60 moved backward until it comes in contact with the pin 10, when the pen can be readily removed. The pen is then reversed and its shank is inserted underneath the sleeve 11, the sleeve is then moved forward toward 65 the end 7 so as to securely place the pen in position and when in this position the nibs lie closely against the surface of the member 5 so that there will be no danger of the same 70 catching in the lining of the pocket and becoming bent or distorted.

If no pen is used the sleeve 11 is prevented 75 from slipping over the end 7 by the pin 9 with which it contacts, the pins 9 and 10 of course, projecting sufficiently beyond the 80 surface of the member 5 to prevent the sleeve 85 from passing thereover.

One of the particular advantages of my 90 penholder is that it is non-absorbent and should a pen point become corroded therein 95 through the action of ink on the pen point and also the coagulation of ink, the holder can be readily thrown into a vessel containing water and boiled to remove such coagulation and permit the removal of the pen 100 point.

Furthermore by using the sleeve formed of 105 a coil spring of non-corrosive material, it is possible to sterilize the holder when the same has been handled by a person having a contagious disease. This is not possible where 110 holders having sleeves made of cork or soft or hard rubber are employed, since the heat, during the sterilization, would readily destroy the same.

Furthermore, it is to be noted that my 115 penholder is absolutely solid from end to end and not provided with slits as is the case in penholders where solid metal sleeves are employed. These slits in a short time become 120 completely filled with coagulated ink, and also with dirt and germs and being very 125 hard to clean, boiling being precluded because they are invariably attached to wooden 130 holders.

If found desirable the tapered member 5 135 may be made of other material than metal.

Having fully described my invention, what 140 I claim is:—

1. A penholder comprising an elongated 145 solid tapering member circular in cross section, the exterior surface of its larger end

adapted to fit the interior surface of a pen point, a sleeve having the same taper as said member and formed of a single strand of closely coiled spring wire slidably mounted on the large end of said member and adapted to pass over the outer surface of a pen point when positioned on said member, a pin located near the large end of said member, a second pin spaced longitudinally of said tapering member from the first mentioned pin, said pins adapted to limit the longitudinal movement of said sleeve in either direction whereby a pen point can be clamped securely for use and in reversed position when not in use.

2. A penholder comprising an elongated solid non-elastic tapering member circular in cross section, the exterior of its larger end adapted to fit the interior surface of a pen point, a sleeve having the same taper and of

slightly larger diameter than said member at its greatest diameter formed of a single strand of closely coiled wire slidably mounted on said member adjacent its large end and adapted to pass over the outer surface of a pen point when positioned on said member, a pin located adjacent the large end of said member, a second pin spaced longitudinally of said member from said first mentioned pin, said pins adapted to limit the longitudinal movement of said sleeve in either direction on said member whereby a pen point can be securely clamped for use on said member and also securely clamped on said member in reversed position when not in use thereby permitting the penholder to be carried in the pocket.

In testimony whereof, I have signed my name to this specification.

NICHOLAS C. STARK.
